UNITED STATES PATENT OFFICE.

WALTER F. ROGERS, OF CHICAGO, ILLINOIS.

OVEN DOOR.

Application filed July 6, 1927. Serial No. 201,835.

- This invention relates to oven door construction and its main objects are to provide an improved type of oven door; to provide an oven door which may be readily assembled, or dismantled for repair purposes; and to provide an oven door and door frame having improved means for tensioning the opening and closing movement of the oven door.
- 10 An illustrative embodiment of the invention is shown in the accompanying drawings, wherein:—
- Fig. 1 is a front elevation of the oven door and its frame.
- 15 Fig. 2 is an enlarged sectional view thereof taken on line 2—2 of Fig. 1, the door, in its opened position, being shown in dotted lines.
- 20 Fig. 3 is an enlarged fragmentary rear view of a lower corner of the door and its frame.
- 25 Fig. 4 is an enlarged perspective fragmentary rear view of the opposite lower corner of the door and its frame.
- 30 Fig. 5 is an enlarged view of the oven door, partly in section, shown mounted on its frame, its opened position being shown in dotted lines.
- 35 Heretofore, in oven construction, it has been the practice to incorporate therein a tension spring which acts between the door and door-frame in such manner as to assist in lifting or closing the door when moved from its open or horizontal position to its closed or vertical position. A coiled tension spring has commonly been employed for this purpose and was located usually in the channel-shaped door-frame.
- 40 Due to repeated heating and cooling of this spring, it has been found that it often becomes crystallized and breaks and when this happens it has been necessary to remove the entire door-frame from the oven in order to replace the broken spring.
- 45 In the present construction, shown in this invention, the coiled tension spring is located in the channel shaped marginal frame of the door itself and when a spring breaks and needs to be replaced, it is only necessary to remove the sheet metal lining of the door in order to make the necessary replacement, thereby avoiding the dismantling of the door-frame.
- 50 In the construction shown in the drawings an oven door-frame 1 of channel construction and of rectangular form is secured
- and set into a sheet metal oven compartment 2.
- An oven door 3 is provided with a handle 4 and is hingedly mounted on the frame 1 by means of a pair of trunnions 5 and 6 which project laterally and are supported in recesses 7. A sheet metal lining 3.1 is mounted on the inside of the door 3.
- The trunnion 5 is detachably secured to the oven door by means of the screws 8 in order to provide ready dismantling and assembly of the door and its frame. The other trunnion 6 is integrally cast with the oven door and each trunnion is provided with an outwardly projecting integrally cast lug 9 which contacts with laterally projecting stops 10, cast integrally with the channel door-frame, when the door is in its fully opened or horizontal position.
- 55 Spring tensioned means tending to resist the opening of said door comprises a helical spring 11 secured at one of its ends to the inside of the door so as to be covered by the door lining (not shown) by means of the screw 12 and at its other end to a link 13 slidable within a bearing block 14 and in the direction of the spring tension. The link 13 is pivotally connected at 15^A to an arcuate link 15 which is pivotally secured at its other end to the door-frame by means of the screw 16. Means for limiting the movement of the arcuate link comprises the headed stud 17 set into the door-frame. The arcuate link 15 contacts with the headed stud 17 before the door is in its fully opened position and the tension of the spring is thereby increased during the rest of the opening movement of the door. Movement of the door in this direction is limited by the contacting of the lugs 9 with their respective stops 10. As shown in Fig. 5 of the drawings, when the door 3 is opened to a horizontal position, the point of pivotal connection 15^A passes through the arc of a circle, whose center is the pivot 16, whereas, if the point 15^A were to be swung through an arc of a circle whose center is the pivot 6 of the door, the two arcs would diverge as shown in dotted outline. The amount of such divergence is the amount the tension spring 11 is stretched before the link 15 contacts with the stud 17.
- 60 It will, therefore, be seen that the construction herein shown and described provides an oven door which may be readily assembled or dismantled for repair purposes.

such as the replacement of the spring tensioned means in the event that the spring breaks or becomes ineffective for any reason, and that improved means are provided for tensioning the opening and closing movement of the oven door.

While but one specific embodiment of this invention has been herein shown and described, it will be understood that 10 numerous details of the construction shown may be altered or omitted without departing from the spirit of this invention as defined by the following claims.

I claim:

- 15 1. In an oven door and frame therefor, means to provide for the opening and closing movement of said door and spring tensioned means resisting the opening of said door comprising a spring secured at one of its ends to the door and at its other end to an arcuate link, said link being connected to said door-frame.
- 20 2. In an oven door and frame therefor, means to provide for the opening and closing movement of said door and spring tensioned means resisting the opening of said door

comprising a spring secured at one of its ends to the door and at its other end to an arcuate link, said link being connected to said door frame, and means for limiting 30 the movement of the arcuate link to increase the tension on said spring.

3. In an oven door and frame therefor, means to provide for the opening and closing movement of said door and spring tensioned means resisting the opening of said door comprising a spring secured at one of its ends to the door and at its other end to a link slideable within a bearing and in the direction of the spring tension, said link 40 being pivotally connected to an arcuate link connected to said door-frame.

4. The combination of an oven door-frame, a door swingably mounted on said frame, and a coiled tension spring mounted 45 on the inside of said door so as to be covered by the door lining and having one end connected to said frame for aiding the closing of said door.

Signed at Chicago this 24th day of June, 50
1927.

WALTER F. ROGERS.
